UNITED STATES PATENT OFFICE.

ARTHUR J. ADAMS, OF HUNTINGTON PARK, CALIFORNIA.

WAVE MOTOR.

Application filed August 27, 1925. Serial No. 52,900.

My invention relates to improvements in motors which are actuated by the rise and fall of waves, such as those of the ocean, and the primary object of the invention is to provide an exceptionally simple and inexpensive, yet an efficient and reliable machine whereby the movements of the waves are utilized to continually wind spring means, the latter being then employed to rotate the shaft, by means of which a generator or other machine may be driven.

With the foregoing in view, the invention resides in the novel subject matter herein-after described and claimed, the description being supplemented by the accompanying drawings.

Figure 1 is a side elevation of a wave motor constructed in accordance with my invention.

Figure 2 is a vertical transverse sectional view on line 2—2 of Fig. 1.

Figure 3 is a detail longitudinal sectional view taken substantially on line 3—3 of Fig. 2.

Figure 4 is a detail vertical section on line 4—4 of Fig. 1.

In the drawings above briefly described, the numeral 1 designates a horizontally disposed shaft which is rotatably supported in bearings 2. These bearings may be supported in any desired manner and I have shown them carried by the upper ends of the posts 3 which rise from a suitable frame structure 4, such as a wharf. Any desired number of drums 5 are rotatably mounted on the shaft 1 and are free to turn with respect thereto, and connected to each drum, is a depending cable 6 having a float 7, said float being loosely connected by appropriate

cables or the like 8, with the frame structure 4. Another cable 9 is connected to each drum 5 and at its upper end is wound upon a spring-rotated drum 10 which is shown supported by standards 11 rising from the frame structure 4, but may be mounted in any desired manner. When the float 7 descends, the cable 6 unwinds from the drum 5 and rotates the latter, and at the same time, the cable 9 is wound upon said drum,

so that it must unwind from the drum 10, thus placing the internal spring of the latter under tension. When the float 7 again rises, this spring tension rotates the drum 10 and through the instrumentality of the cable 9, the drum 5 is correspondingly rotated, so

that slack in the cable 6 is taken up and the latter is in readiness to again rotate the drum 5 forwardly upon the next descent of the float.

At each end of each drum 5, I mount a spring barrel 12 which preferably contains two spiral springs 13 having connection both with the barrel and with the shaft 1, upon which the barrel is free to rotate. Spring-pressed pawls 14, pivoted to the ends of the drums 5, co-act with portions of the barrels 12 to rotate the latter in a direction to wind the springs 13, when the float 7 descends, and spring-pressed dogs 15 are provided to hold these barrels against retrograde movement, thus holding the springs 13 to the extent to which they have been wound and permitting their tension to act upon the shaft 1 to rotate the latter. Thus, as long as the float 7 is moved up and down by the waves, said float, the spring-rotated drum 10, and the cables 6 and 9, serve to turn the drum 5 first in one direction and then in the other so that the pawls 14 rotate the barrels 12 in a step-by-step manner, keeping the springs 13 wound and causing the latter to exert their power to turn the shaft 1 smoothly and steadily.

All of the parts above mentioned, are constructed in a simple and inexpensive, yet a durable manner, as will be clear from the following. In the formation of the drum 5, I take an elongated metal plate and bend it to form a cylinder 16, the ends of the plate however, being left in slightly spaced relation to form a longitudinal slot 17 at the periphery of this cylinder. Hooks 18 on the ends of the cables 6 and 9, hook into this slot to connect said cables with the cylinder.

Two metal disks 19, preferably having flared edges, contact with the ends of the cylinder 16 and project beyond the periphery of this cylinder to guide the cables 6 and 9, said cylinder and disks being tightly secured together and held in concentric relation, by a plurality of bolts 20 which engage the inner side of the cylinder and pass through circumferentially spaced openings in the disks. At their centers, these disks are preferably provided with hubs 21 which may be integral therewith or joined thereto in any desired manner, to turn freely upon the shaft 1.

The pawls 14 are connected pivotally with the peripheral portions of the disk 19 by bolts or the like 22, and appropriate springs 110

23 are associated with said pawls for yieldably urging them toward the barrels 12.

The drum 10 is composed of a metal plate bent to form a cylinder 16', a pair of end disks 19' and bolts 20', these parts being related in the same manner as the parts 16, 19 and 20 of the drum 5. The ends of the plate forming the cylinder 16', are spaced apart to provide a slot 17' into which a hook 18' on the cable 9 is hooked. Also engaged with this slot, is a hook 24 on the end of a spiral spring 25 which is located within the cylinder 16', the inner end of said spring having any appropriate connection with a shaft 26 upon which the drum is rotatably supported.

Each barrel 12 includes a metal plate bent to form a cylinder 16^a and having the ends of said plate spaced apart to form a slot 17^a at the periphery of said cylinder. Disks 19^a contact with the ends of this cylinder and are held against the same by bolts 20^a which are disposed at the exterior of the barrel, said bolts passing through the peripheral portions of the disks so as to tightly secure these disks and the cylinder 16^a in assembled relation. The bolts 20^a are co-operable with the pawls 14, and act very much like ratchet teeth. Also, the dog 15 is co-operable with the bolts 20^a. It will thus be seen that these bolts perform a multiple function which is very unique. The slots 17^a receive hooks 24^a on the outer ends of the springs 13, the inner ends of said springs having any desired connections with the shaft 1.

It will be seen from the foregoing that a simple and inexpensive construction has been provided, yet that it will be efficient, particularly when several sets of the spring barrels 12 and associated parts, are mounted on a single shaft such as 1. Then, it will usually be found that at least one of the floats 7 is operating to positively turn the spring barrels of one set, while upward movement of the other float or floats is taking place and the pawls thereof are clicking reversely over the bolts 20^a, in readiness to again grip the same and turn the spring-winding barrels when descent of the rising float or floats takes place. Even in exceptionally rough water, the machine will operate advantageously, as the floats 7 are allowed a great deal of leeway in their movements, due to the slack of the cables 8. Moreover, the shaping of the floats is such that the action of the water laterally against them has a tendency to produce upward movements thereof, which is advantageous as the more vertical movements the floats possess, the greater the efficiency of the machine. Each float is of circular outline and my reason for making the top of the float of greater diameter than its bottom and providing it with an outwardly inclined side wall, is that when a fast rush of water or a breaker comes in

contact with the float, the force of the water is deflected by the angle of the side wall, lifting the float to the top of the water instead of forcing it in the direction in which the water is flowing. My reason for having anchorage loops 7^a at the outer edge of the top of the float and also loops 7^b at its bottom, and connecting cables 8 with top loops 7^a and short cables 8^a with loops 7^b and with cables 8 at points spaced from the float is that when the float gets to the full length of the anchor cable 8, the float tips upward, being canted in this manner by the pull on the bottom cable 8^a, thus causing the water to lift the float and allowing the water to pass under such float. Without this bottom anchorage, breakers would submerge the float and the force of the water would so turn said float about a horizontal axis as to permit the full force of the breakers to come in contact with the top face of said float. This would have a tendency to break the anchorage or otherwise damage the machine. Loose anchorage is provided for each float so that the latter may move around in any direction, according to the movement of the water, and as long as these floats are moving in any direction from a central position, they are winding the springs of the spring barrels. As soon as any float reaches the end of travel permitted by its anchorage, such anchorage tips the float and causes the water to act as a wedge between the larger circumference of the float and the water below the float, thereby tilting the float upwardly and causing the water to slide underneath, without any great resistance against the float to cause breakage or damage.

In tests of a full sized working machine embodying eight floats, each provided with anchoring cables, my experience was that in less than ten minutes after placing the floats on the ocean, three acetylene-welded anchors on the floats, for the anchoring cables, were ripped off. This however, was before I conceived the idea of providing the arrangement of cables herein disclosed, in which the main anchoring cables are connected with the upper portion of the float and the auxiliary cables to the bottom portion thereof. After making this change, no further difficulty was encountered with regard to ripping loose of the cable anchors from the floats. Before the use of this improved arrangement of cables, the flat sides of the floats would often receive the direct force of the breakers, but with said arrangement of cables, this is impossible and the floats are so controlled that at all times, the water, even of forcible and high breakers, may slide freely under the floats, without any severe tendency toward the breaking of cable anchors or cables.

On account of the good results obtainable from the details disclosed, they are preferably followed. However, within the scope

of the invention as claimed, modifications may be made.

I claim:

1. In a wave motor, a supporting structure, a drum rotatably mounted on said structure, a cable wound on and depending from said drum for rotating it, a float on the lower end of said cable having a relatively large diameter at its top, a comparatively small diameter at its bottom and an inwardly declined side wall from said top to said bottom, and anchoring cables connected with the supporting structure and extending radially from the float to said structure, said cables having bifurcated lower ends connected with the periphery of the float at the upper and lower edges of said side wall respectively.

2. A wave motor comprising a supporting

structure, a shaft rotatably mounted thereon, 20 a drum rotatable upon said shaft, a one-way driving connection between the drum and shaft, a float-actuated cable wound in one direction upon said drum for turning the latter in shaft-driving direction upon descent of the float, a second cable wound in the opposite direction upon the drum, a second drum spaced from the first named drum, the second cable being wound upon said second drum, and spring means connected 30 with said second drum for rotating it in cable-winding direction, whereby the second drum and cable will rotate the first named drum in cable-winding direction upon each ascent of the float-actuated cable. 35

In testimony whereof I have hereunto affixed my signature.

ARTHUR J. ADAMS.
